CLAIM

The ornamental design for a combined trophy ball and picture display stand, as shown and described.

DESCRIPTION

FIG. 1 is a perspective view of a combined trophy ball and picture display stand showing my new design;

FIG. 2 is a front elevational view thereof;

FIG. 3 is a right side elevational view thereof;

FIG. 4 is a rear elevational view thereof;

FIG. 5 is a bottom plan view thereof;

FIG. 6 is a top plan view thereof;

FIG. 7 is a perspective view of a second embodiment of FIG. 1;

FIG. 8 is a front elevational view of the embodiment of FIG. 7;

FIG. 9 is a right side elevational view of the embodiment of FIG. 7;

FIG. 10 is a rear elevational view of the embodiment of FIG. 7;

FIG. 11 is a bottom plan view of the embodiment of FIG. 7;

FIG. 12 is a top plan view of the embodiment of FIG. 7.

FIG. 13 is a perspective view of a third embodiment of FIG. 1;

FIG. 14 is a front elevational view of the embodiment of FIG. 13;

FIG. 15 is a right side elevational view of the embodiment of FIG. 13;

FIG. 16 is a rear elevational view of the embodiment of FIG. 13;

FIG. 17 is a bottom plan view of the embodiment of FIG. 13; and

FIG. 18 is a top plan view of the embodiment of FIG. 13.
